UNITED STATES PATENT OFFICE.

ROBERT J. SMIRLE, OF SAN FRANCISCO, CALIFORNIA.

WIRE-UNCOILING APPARATUS.

1,312,058.

Specification of Letters Patent.

Patented Aug. 5, 1919.

Application filed March 13, 1919. Serial No. 282,264.

To all whom it may concern:

Be it known that I, ROBERT J. SMIRLE, a citizen of Canada, and a resident of the city and county of San Francisco and State of California, have invented a certain new and useful Wire-Uncoiling Apparatus, of which the following is a specification.

The invention relates to apparatus for uncoiling a coil of wire.

10 An object of the invention is to provide an apparatus for uncoiling a coil of wire without kinking or tangling the wire.

Another object of the invention is to provide a wire uncoiling apparatus in which 15 the coil of wire remains stationary.

The invention possesses other advantageous features, some of which, with the foregoing will be set forth at length in the following description where I shall outline in 20 full, that form of the invention which I have selected for illustration in the drawings accompanying and forming part of the present specification. In said drawings I have shown one specific form of the apparatus of my invention, but it is to be understood that I do not limit myself to such 25 form, since the invention, as set forth in the claims, may be embodied in a plurality of forms.

30 Referring to said drawings—

Figure 1 is an elevation of the apparatus.

Fig. 2 is a vertical section of the apparatus.

35 Fig. 3 is a top or plan view of the apparatus.

The apparatus of my invention comprises a suitable base 2, preferably metallic, on which the coil of wire 3 is laid. The base is preferably circular and is provided at 40 the periphery with an elevated portion or flange 4, forming a seat on which the coil of wire is disposed. Arranged at the center of the base and preferably integral therewith is a stud 5, preferably conical in shape. 45 The coil of wire surrounds the stud which, with the base, causes the coil to remain more or less intact.

Rotatably disposed in the stud and extending from the upper end thereof is a 50 curved pipe or conduit 6, which is bent downward toward the coil. At its end the pipe is bent into an arc 7, which ends substantially tangentially with respect to the coil. The portion 8 of the pipe which is disposed within the stud is straight and 55 may seat within the stud or the pipe may be

provided with a collar 9 which bears against the top of the stud. The wire to be uncoiled is passed into the pipe 6 at the lower end which directly overlies the coil and passes 60 out through an aperture 12 at the upper end of the bent pipe.

Arranged above the stud 5 is a tubular guide 13, usually a piece of bent pipe, through which the wire passes and in which 65 the direction of movement of the wire is changed from substantially vertical to substantially horizontal or to any other desired direction. The guide 13 is mounted on a suitable support 14, which may be secured 70 to the base 2, and is movable or rotatable on the support for reasons which will herein-after become apparent.

The inlet end 15 of the guide 13 is disposed directly over the bend in the pipe 6, so 75 that, should the wire become tangled or kinked in uncoiling so that it will not enter the pipe 6, the movement of the wire through the guide 13 will cause the pipe 6 to move rapidly upward and strike the inlet end of the guide. This action invariably loosens the wire and overcomes the obstruction. The pipe 6 is therefore not only rotatable, so that the lower end thereof can follow around the coil as the wire is drawn, 85 but is also movable vertically to release the wire in the event that it becomes stuck in the pipe or in entering the pipe.

When it is necessary to place a coil of wire on the base, the guide 13 is moved to 90 one side to permit the pipe to be withdrawn from the stud, the pipe is then withdrawn and the coil placed. The pipe is then reinserted and the guide moved back to position. The length of the pipe disposed within the 95 stud is such that it is not entirely withdrawn from the stud when the pipe strikes the guide so that it falls back to its normal position.

I claim:

1. A wire uncoiling apparatus comprising a base, a stud arranged centrally on said base and adapted to be surrounded by the coil of wire, and a conduit rotatably mounted on said stud and movable vertically with 105 respect thereto having its lower end overlying the coil of wire and curved forward to receive the wire as it uncoils.

2. A wire uncoiling apparatus comprising a base, a stud arranged centrally on said 110 base and adapted to be surrounded by the coil of wire, a conduit through which the

100

105

110

wire passes rotatably mounted on said stud and movable vertically with respect thereto and a guide for the wire arranged above said conduit.

5. 3. A wire uncoiling apparatus comprising a base, a stud arranged centrally on said base and adapted to be surrounded by a coil of wire, a conduit through which the wire passes mounted on said stud for rotational and vertical movement with respect thereto and a guide for the wire arranged above said conduit in position to be struck by said conduit as it moves vertically.

4. A wire uncoiling apparatus comprising 15 a base, a conical stud arranged centrally on said base and adapted to be surrounded by the coil of wire, a bent pipe mounted on said stud for vertical and rotational movement with respect thereto, said pipe being bent 20 downward so that the end thereof is disposed adjacent the coil of wire, said end being curved forwardly to receive the uncoiling wire and means for limiting the vertical movement of the pipe.

25 5. A wire uncoiling apparatus comprising a base, adapted to receive a coil of wire, a bent pipe through which the wire passes, movable vertically and mounted for rotation with respect to said base arranged above said coil, and means for limiting the vertical movement of said pipe.

6. A wire uncoiling apparatus comprising a base adapted to receive a coil of wire, a bent pipe through which the uncoiled wire passes arranged for rotation concentric with 35 said coil and for vertical movement with respect thereto the lower end of said pipe being disposed above said coil and being curved forward to receive the wire from the coil and means for limiting the vertical 40 movement of the pipe.

7. A wire uncoiling apparatus comprising a circular base having an upstanding peripheral flange, a conical stud disposed centrally with respect to said base and adapted to be 45 surrounded by a coil of wire, a pipe bearing in said stud and being bent downwardly so that its outer end overlies said coil, said pipe being rotatably and vertically movable with respect to said base and being provided at 50 its upper portion with an exit opening for the wire and a wire guide arranged above said pipe and disposed in position to be struck by the upper portion of the bent pipe 55 when said pipe is moved vertically.

In testimony whereof, I have hereunto set my hand at San Francisco, California, this 26th day of February, 1919.

ROBERT J. SMIRLE.
